TOP FRAME FOR AN AQUARIUM

Robert R. Greenwald, 18901 Lahey St.,
Northridge, Calif. 91324

Filed Aug. 12, 1974, Ser. No. 496,595

Term of patent 14 years

Int. Cl. D30—02

U.S. Cl. D30—12

FIG.1.

FIG.2.

FIG.3.

FIG.4.

FIG.6.

FIG.5.

FIG.7.

FIG. 1 is a top plan view of a top frame for an aquarium showing my new design;

FIG. 2 is a front elevational view;

FIG. 3 is a bottom plan view;

FIG. 4 is a side elevational view;

FIG. 5 is an enlarged scale fragmentary cross-sectional view taken along the line 5—5 of FIG. 1;

FIG. 6 is an enlarged scale fragmentary cross-sectional view taken along the line 6—6 of FIG. 1; and

FIG. 7 is an enlarged scale fragmentary cross-sectional view taken along the line 7—7 of FIG. 1.

I claim:

The ornamental design for a top frame for an aquarium, substantially as shown and described.
